UNITED STATES PATENT OFFICE.

OTIS L. FOWLER, OF LYNBROOK, NEW YORK.

AIR COMPRESSOR.

Application filed March 9, 1923. Serial No. 623,839.

To all whom it may concern:

Be it known that I, OTIS L. FOWLER, a citizen of the United States, residing at Lynbrook, in the county of Nassau and State of New York, have invented certain new and useful Improvements in Air Compressors, of which the following is a specification.

My invention relates generally to air or gas compressors and the object of my improvements is to provide a device of this class which shall be of simple construction and economical and efficient in operation.

In carrying my invention into effect, I utilize the expansive force of steam or other suitable expanding gas or vapor by applying it directly to compress the air instead of employing a piston or other mechanical compressing device and I also provide means for conserving and utilizing practically all of such expansive force in effecting the compression. In this manner a very economical method of operation is provided with a minimum of expenditure for applied power.

The invention will be best understood by reference to the accompanying drawings illustrating an embodiment thereof, Fig. 1 of which shows an end elevation of one form of the device and Fig. 2 a longitudinal section of the same on the line, 2-2 Fig. 1. Fig. 3 is a sectional view showing explosion chambers which may be used when an explosive gas is used to effect the compression.

Fig. 4 shows a vertical cross section and Fig. 5 a longitudinal section of a modified form of the device in which the compression chambers are arranged as a centrifugal fan, the exhaust fan or blower shown in Figs. 1 and 2 being omitted.

Fig. 6 shows an end view and Fig. 7 a vertical section on the line 7-7, of Fig. 6, of a further modification in which two sets or series of compression chambers are employed.

Referring to the drawings, A, indicates a rotatable member, mounted on a shaft *a* and provided with means to effect its rotation as a pulley, P.

The member, A, is composed of a series of separated chambers, B, B, extending longitudinally thereof, the ends of which, during a portion of the revolution of the member, A, are closed by the face plates, C, C', and during another portion of such revolution when they are opposite the ports, D, D, are open to atmosphere and to the

chamber, E, in which is an exhaust fan or blower, F, (Fig. 2) mounted on the shaft, *a*. The compression of the air in the chambers, B, is effected by the admission thereto, in succession, of an expansible gas or vapor, as steam through steam pipe, G, the compressed air, or a portion of it being forced out through pipe, H, to the point of use or to a storage chamber, I. When a chamber in which air has been compressed passes away from connection with the source of pressure, it still contains air under pressure, and this is distributed to raise the pressure in other chambers.

Following the course of one of the chambers, B, through one revolution of the member, A, when it is in either of the positions indicated at 1, 2, 3, 4, it is connected with atmosphere through the ports, D, D, and is filled with air at atmospheric pressure. As it passes out of position, 5, it is connected with passage, K, which extends through the face plate, C, and the other end of which is, at the moment, connected with a downwardly moving chamber in the position, 12, which contains air under pressure above atmosphere.

The pressure in the two chambers is equalized, that in the upward moving chamber being raised. Before the upward moving chamber passes out of connection with passage, K, it is connected therethrough with the next succeeding downwardly moving chamber thus receiving a further increment of pressure. In the same manner the upwardly moving chamber is successively connected through each of the passages, L, M, with two downwardly moving chambers each of which contains air at higher pressure than that in the upwardly moving chamber, so that it receives successive further increments of pressure. As the chamber passes from position, 8, to position, 9, it is connected with the port of steam pipe, G, steam from which entering the chamber compresses the air therein to its maximum, forcing compressed air out through pipe, H, to the point of utilization or to reservoir, I. As the chamber moves away from connection with steam pipe, G, and begins its downward movement, it still contains air under pressure which, as it successively passes the ports of passages, M, L, K, in the positions, 10, 11, 12 is given up to upwardly moving chambers connected with the opposite ends of said passages.

When the chamber reaches position, 1, it is again connected with the open air and any steam, or other vapors or gases therein, is swept out.

Instead of using the expansive force of steam to compress the air other expansive gases may be employed. Thus as illustrated in Figs. 1 and 3, an explosive liquid fuel may be fed in as from a small reservoir,

10 N, in which the fuel is under pressure from the air in reservoir, I, through pipe, b. As a chamber, B, passes position, 8, the fuel is drawn in at high velocity through Venturi tube, d, and atomized and exploded as

15 by an electric spark as indicated at, e, thus compressing the air. Or the expansive force of internal or external combustion applied to a chamber, O, arranged to connect with chambers, B, as they pass position, 8, may

20 be employed as illustrated in Fig. 5. In either case the manner of compressing the air by applying directly thereto the expansive force of a gas or vapor is the same and the products of combustion or other gas or vapor employed and remaining in the compression chamber are swept out as the chamber passes the ports, D, D.

A modification of the device is illustrated in Figures 4 and 5. In this case the blower or exhaust fan, F, is omitted and the chambers, B, are arranged as a centrifugal fan. If desired compressed air from reservoir, I, may be employed for effecting the rotation of member, A, by means of a small engine as indicated at, R, Fig. 5.

A further modification is illustrated in Figs. 6 and 7. In this form of construction a second series of compression chambers, B', B', is provided outside of the series of chambers, B, B.

The primary or maximum compression may, as shown, be effected in one of the chambers of the series, B. As the chamber moves away from the point of maximum compression it successively gives up pressure through passages M, I, K, to chambers on the other side of the member, A, which are approaching the point where maximum compression is effected, in the manner above described. The chamber then reaches a point where it is connected with the passages, D', D', and through these with one of the chambers, B'. The pressure in chamber, B, which may at this point equal one-third of the maximum pressure, is equalized with that in chamber, B', and the gases or vapors are swept out from chamber B, into chamber, B'. Chamber, B', in turn, when in positions, 11, 12, gives up pressure, through passages, K', L', to corresponding chambers on the opposite side of member, A, and, in passing through positions 1, 2, 3, 4, is swept clean of gases and vapors and is filled with fresh air. By this means a greater proportion of the pressure induced

by the primary application of pressure to the air is conserved, than where a single series of chambers is employed.

It will be evident that various modifications of the details of the apparatus as shown may be made without departing from the invention as expressed in the accompanying claims.

Thus by connecting the ports, D, D, with a vacuum chamber instead of with the open air, the apparatus may be used as a vacuum pump, as will be readily understood by those skilled in the art, and the claims are intended to cover the device as applied to such purpose.

Having thus described my invention what I claim as new and desire to secure by Letters Patent is:—

1. The method of compressing air which consists in progressively increasing the pressure in an air chamber by successively connecting such chamber with a series of separate chambers each containing air at a higher pressure than that in the first mentioned chamber and finally subjecting the air in said chamber at the time of such connection to gas or vapor pressure to complete the compression of the air therein.

2. The method of obtaining compressed air which consists in compressing the air in a chamber by admitting thereto gas or vapor under pressure and drawing off a portion of the compressed air therefrom and then successively connecting such chamber with a series of other chambers containing air at lower pressure than that in the first mentioned chamber so as to raise the air pressure in said other chambers.

3. In a device for compressing air the combination of a compression chamber, means for applying a gas or vapor under pressure directly to the air in such chamber so as to compress the same, means for drawing off a portion of the compressed air from the chamber and means for utilizing the pressure remaining in said chamber to raise the air pressure in other similar chambers.

4. In an air compressing device the combination of a rotatable member composed of a series of chambers, ports arranged to successively connect said chambers with the open air during a portion of the revolution of said member, means for closing the chambers from the air during another portion of the revolution of said member, and means for successively compressing the air in said chambers.

5. In a device for compressing air the combination of a rotatable member composed of a series of chambers, ports arranged to successively connect said chambers with the open air during a portion of the revolution of said member, means for closing the chambers from the open air during another portion of the revolution of said member, means

for progressively increasing the air pressure in said chambers by means of air at higher pressure in other of said chambers and means for raising the air pressure to a maximum by admitting thereto a gas or vapor under pressure.

6. In a device for compressing air the combination of a rotatable member composed of a series of chambers, and plates arranged to close said chambers and provided with passages whereby chambers on one side of said member are connected with chambers on the other side of said member.

7. In a device for compressing air the combination of a series of compression chambers, a second series of chambers arranged outside of the first named series of chambers, means for compressing air in the first named series of chambers by admitting

thereto in succession gas or vapor under pressure means for transferring the gas or vapor from the first named series of chambers to the second series of chambers and means for discharging the gas or vapor from the second series of chambers to the atmosphere.

8. In an air compressing device the combination of two sets of compression chambers, means for compressing air in chambers of one set by the application thereto of a gas or vapor under pressure, means for discharging the gas or vapor from the chambers of one set to the chambers of the other set and means for discharging such gas or vapor to the open air.

In testimony whereof I affix my signature, this 5th day of March 1923.

OTIS L. FOWLER.
